UNITED STATES PATENT OFFICE.

JABEZ BURNS, OF NEW YORK, AND CHARLES S. HIGGINS AND WILLIAM B. HIGGINS, OF BROOKLYN, NEW YORK.

DESIGN FOR SOAP-CAKE.

Specification forming part of Design No. **7,235**, dated March 10, 1874; application filed March 5, 1874.
[Term of Patent 14 years.]

To all whom it may concern:

Be it known that we, JABEZ BURNS, of the city, county, and State of New York, and CHARLES S. HIGGINS and WILLIAM B. HIGGINS, both of Brooklyn, in the county of Kings and State of New York, have invented a new and original Design for Cake of Soap; and we do hereby declare the following to be a full, clear, and exact description thereof, which will enable those skilled in the art to make and use the same, reference being had to the accompanying drawing forming part of this specification, in which drawing—

Figure 1 represents a plan or top view of our cake of soap. Fig. 2 is a transverse section of the same.

Similar letters indicate corresponding parts.

This design relates to a cake of soap made in the form of a banana.

In the drawing, the letter A designates our cake of soap, which is made in the form of a banana. A cake of soap of this shape is novel and peculiar in its appearance, and it can be readily distinguished from cakes of soap made in the ordinary form or shape.

What we claim as new, and desire to secure by Letters Patent, is—

The design for a cake of soap made in the form of a banana, as shown and described.

JABEZ BURNS.
